UNITED STATES PATENT OFFICE

116,818

DESIGN FOR A COMBINED GRAVE MARKER AND URN

Stanley C. Dreher, Cincinnati, Ohio, assignor to
Reliance Art Metal Inc., Cincinnati, Ohio, a
corporation of Ohio

Application July 25, 1938, Serial No. 78,686

Term of patent 3½ years

To all whom it may concern:

Be it known that I, Stanley C. Dreher, a citizen of the United States, residing in Cincinnati, in the county of Hamilton and State of Ohio, have invented a new, original, and ornamental Design for a Combined Grave Marker and Urn, of which the following is a specification, reference being had to the accompanying drawing, forming part thereof.

Fig. 1 is a plan view of a combined grave marker and urn with the urn in inverted position, showing my new design;

Fig. 2 is a perspective view thereof; and

Fig. 3 is a perspective view of the combined grave marker and urn with the urn in upright po-

sition, the portion shown in dotted lines being partly broken away for convenience in illustration.

The essential features of my invention reside in the design of the invertable urn, the floral design of the base harmonizing, when the urn is in inverted position, with the pebbled border design of the supporting tablet, and the shape and contour of the urn, when in upright position, continuing to harmonize with the design of the circular supporting tablet.

I claim:

The ornamental design for a combined grave marker and urn, as shown and described.

STANLEY C. DREHER.
